UNITED STATES PATENT OFFICE.

WILLIAM HORN, OF CHICAGO, ILLINOIS.

CEILING OR WALL CONSTRUCTION FOR FIREPROOF BUILDINGS.

SPECIFICATION forming part of Letters Patent No. 728,919, dated May 26, 1903.

Application filed October 4, 1902. Serial No. 125,864. (No model.)

To all whom it may concern:

Be it known that I, WILLIAM HORN, a citizen of the United States, residing at Chicago, in the county of Cook and State of Illinois, 5 have invented certain new and useful Improvements in Ceiling or Wall Constructions for Fireproof Buildings, of which the following is a specification.

My invention relates, generally speaking, 10 to an improvement in the construction of fireproof buildings wherein the skeleton or supporting elements are formed of iron girders or beams usually employed in commercial structural forms; and my invention relates 15 more particularly to an improved construction of ceilings and partition-walls, the novel feature of the invention residing in an improved form of clip for uniting the intersecting beams and girders constituting the supporting structure for the lathing and plaster. 20

The object of my invention is to provide a clip for this purpose which shall combine superior simplicity and cost of manufacture with increased strength and rigidity, a secondary object of the invention being to provide a clip which shall be more economical of space required therefor than other devices for the same purpose with which I am acquainted. 25

For purposes of convenience I have illustrated my invention in a preferred embodiment thereof in connection with a ceiling construction. 30

In the accompanying drawings, Figure 1 is a vertical transverse section through one of 35 the main ceiling girders or beams, the underlying ceiling-iron and my improved clip for uniting the same to the girder being shown in side elevation. Fig. 2 is a similar view of the same parts as they appear in a plane at 40 right angles to the plane of the parts in Fig. 1. Fig. 3 is a perspective detail of my improved clip, and Fig. 4 is a perspective view of the parts shown by and occupying the relative positions illustrated in Figs. 1 and 2.

Referring to the drawings, 5 designates the usual transverse girder or beam of a ceiling or floor construction, here shown in the form of an I-beam, and 6 designates one of a series 45 of transversely-extending ceiling-irons adapted to have attached thereto some form of metal lathing. This iron, as herein shown,

is in the form of a channel-beam having its web disposed in a vertical plane.

In making my improved clip for uniting the elements 5 and 6 I take a plain flat piece 7, 55 of strap iron or steel, preferably of rectangular form, and cut or punch therethrough at separated points apertures 8 of a size and form to slidingly but comparatively snugly fit the ceiling-iron 6 when the latter is passed through 60 said apertures. I then bend up the two end portions of the strip along lines coincident with the inner or base margins of the apertures 8, thereby forming vertical supporting members 9, and finally I bend over inwardly to- 65 ward each other the upper ends of the up-standing members 9 to form end flanges 10, adapted to overlie and rest upon the lower-most head of the I-beam 5.

The manner in which the parts are assem- 70 bled and their relative location is obvious from the illustration and need not be further described. I will therefore briefly mention a few of the advantages which I believe my invention possesses over other known forms 75 of clips. In the first place, it will be observed that the clip affords a seat or support for the ceiling-iron of an extent equal to the full width of the head of the ceiling-beam. In the second place, the vertical supporting mem- 80 bers 9 of the clip are rigidly tied together at their lower ends. In the third place, my invention enables the upper surface of the ceiling-iron to be brought into direct contact with the under surface of the ceiling beam or 85 girder, thereby affording an economy in the space required for the ceiling structure as compared with constructions now known and used, wherein a part or element of the clip lies between the adjacent surfaces of the 90 beams 5 and 6. In the fourth place, my invention, being of extremely-simple construc-tion and requiring but little cutting and bend-ing of the blank from which it is shaped up, is capable of being produced at a reduced cost 95 as compared with other clips for the same purpose with which I am acquainted. Finally, the clip presents no obstruction to the plaster.

It will be obvious that my improved clip is capable of use with other forms of intersecting beams and irons, such forms necessitat-ing only obvious modifications of the aper-

tures 8 and of the flanges 10 to make them conform to the particular shapes of the beams and irons used. The particular forms herein shown are therefore illustrative merely. It is also obvious that my invention may be employed with equal advantage in the construction of fireproof partition-walls other than floors and ceilings.

I claim—

- 10 1. The combination with the main girder and a transverse beam intersecting the plane of said girder, of a clip for uniting said elements in surface contact, said clip comprising a strip of strap metal having a base equal 15 in length to the width of the adjacent head or flange of the girder and having its end portions bent at right angles to the base and apertured to receive the transverse beam, and further having the free extremities of said 20 end portions bent inwardly to embrace the margin of the head of the girder, substantially as described.

2. The combination with the main girder and a transverse beam intersecting the plane

of said girder, of a clip for uniting said elements in surface contact, said clip comprising a strip of strap metal having a flat base forming a seat for the beam and having its end portions bent at right angles to the base and apertured to receive the beam, the lower 30 margins of said apertures being substantially coincident with the plane of the base, and said strip further having the free extremities of said end portions bent inwardly to embrace the margin of the head of the girder, substantially as described.

3. The herein-described clip comprising a central flat seat, apertured end portions disposed at right angles to said seat on the same side thereof, and inwardly-turned flanges on 40 the free extremities of said end portions, the whole being formed up from an integral flat strip of strap metal for the purpose specified.

WILLIAM HORN.
